GAS BURNER

Fred A. Nemec, Whittier, Calif.

Application November 11, 1935, Serial No. 49,198

6 Claims. (Cl. 158—7)

This invention relates to improvements in a burner construction for furnaces.

The general object of this invention is to provide a novel firing tube assembly for gas burners.

Another object of the invention is to provide a novel firing tube for a gas burner.

An additional object of my invention is to provide novel means for supporting a plurality of burner tubes in an operative position.

Other objects and the advantages of this invention will be apparent from the following description taken in connection with the accompanying drawing wherein:

15 Fig. 1 is a fragmentary section through a gas furnace showing my improved burner assembly therein;

Fig. 2 is a fragmentary face view of the apparatus shown in Fig. 1;

20 Fig. 3 is a fragmentary enlarged section through the tube section, and

Fig. 4 is a rear view of the parts shown in Fig. 3.

25 Referring to the drawing by reference characters I have indicated a gas furnace generally at 10. The furnace 10 is of the type fired from the front and has a firing aperture 12 therein. At the upper and lower surfaces of the aperture 12 metal plates 13 are provided.

30 In the accompanying drawing I have indicated my burners generally at 14. As shown each of the burners 14 includes a metal tube section, or tile burner tube holder 15 which is adapted to support a plurality of tile burner tubes 16. Each tube section 15 includes end plate portions 17 and, as shown, has two rows of four tile apertures 18 therein intermediate the end plates. Between the tile apertures 18 the tube sections have apertures 19 therein and the metal surrounding the tile apertures 18 is preferably curved so that when two sets of tube sections 15 are placed side by side, apertures 20, similar to the apertures 19 are formed between the two tube sections. (See Fig. 2).

45 Adjacent the top and bottom of the tube section intermediate the tile apertures the tube section includes a lug 22 which has a threaded aperture 23 therein and adjacent each end the top and bottom plate portions have an aperture 24 therein.

50 As shown each of the tile burner tubes 16 comprises a substantially cylindrical body portion 25 having an aperture 26 therethrough which includes a counter bored portion 26'. The body 25 further includes an enlarged shoulder 27 which

terminates in an enlarged flange portion 28. The tile tubes 16 are supported by the tube sections 15 with the tube shoulders 27 positioned in the tube section apertures 18 and with the tube flanges 28 engaging the face of the tube 5 section.

The tube section apertures 18 and the tube shoulders 27 are formed slightly elliptical as shown in Fig. 4 and after a tube 16 has been positioned in a tube section aperture 18 it is rotated until it firmly engages the side walls of the tube section aperture as shown at A in Fig. 4.

From the foregoing it will be seen that the tube sections completely surround a portion of each of the tile tubes 16 and even should a tube become 15 cracked it will not fall out of the tube section. Furthermore, the flanges 28 of the tile tubes prevent the tubes from accidentally sliding through the tube sections.

When installing a tube section 15 in a furnace such as indicated at 10 the tube section is positioned between the plates 13 and secured thereto by bolts 29 positioned in the apertures 17 and then another tube section 15 is positioned beside the first and similarly secured to the plates 13 and so on until the required number of tube sections are in position. Thereafter the tile firing tubes 16 are positioned in the tube section apertures 18 as previously described.

Each of the burner units 14 further includes 30 a fuel distributing manifold 30 which includes a vertical conduit portion 31 having horizontal conduit portions 32 thereon, one for each tier of firing tiles. Each of the horizontal conduits includes adjacent each end a fuel jet 33 which is 35 substantially concentric with its associated firing tube 16. The manifold 30 further includes upper and lower leg portions 34 having right angularly extending arms 34' thereon which engage the tube section 15. The manifold legs 34 are 40 secured to the tube section by bolts 35 which are positioned in the threaded apertures 23 of the tube section.

45 Adjacent each of the horizontal conduit portions on the vertical conduit portion and between the jets 33 the manifold 30 includes a lug 35' which extends therefrom in the same direction as the arms 34'.

The lugs 35' prevent firing tubes 16 from accidentally working out of the tube sections 14. 50

Fuel is conveyed to each of the manifolds 30 by a conduit 36 which at one end communicates with the interior of the vertical conduit 31 and at the opposite end communicates with the interior of a fuel supply pipe 37. Each of the conduits 36 55

preferably has a shut off valve 38 interposed therein.

By providing the counter bored portion 26' in the tile firing tubes 16 a Venturi effect is produced in each of the tubes when the burner is operating.

By providing the apertures 19 in each of the tube sections 15 and the apertures 20 between the tube sections passageways for draft air past the tube sections are provided for.

10 Although I have shown the tube section 15 as adapted to support eight tile firing tubes in two rows of four tiers it will be understood that the number of tile tubes and the particular positioning thereof may be varied to fit various conditions.

15 At times it may be desirable to form a burner assembly without the tile burner tubes 16 and when such a burner is desired the tube sections 14 and the manifolds 30 are assembled as previously described with the tile burner tubes omitted.

20 From the foregoing it will be apparent that I have provided a novel burner unit for gas furnaces which is simple in construction and highly efficient in use.

25 Having thus described my invention I claim:

1. A burner including a burner tube holder, said holder having a plurality of apertures therein, said apertures being slightly elliptical in shape and a plurality of tile burner tubes, each of said tubes comprising a substantially cylindrical body portion having an aperture therethrough, said body having an enlarged shoulder thereon terminating in an enlarged flange portion, said tube shoulder being slightly elliptical in shape, said tubes being mounted on said holder with said shoulders thereof positioned in said holder apertures and rotated to tightly engage the surfaces of said holder apertures.

30 2. In combination with a gas furnace having a firing aperture therein, a burner including a burner tube holder, a plurality of burner tubes and a fuel manifold, said holder having a plurality of tile apertures therein, each of said tubes comprising a substantially cylindrical body portion having a central aperture, said body terminating in an enlarged flange, said tubes being mounted on said holder with said shoulders thereof positioned in said holder apertures, said fuel manifold having lugs thereon adapted to engage a burner tube to prevent accidental displacement thereof.

35 3. For use with a burner tube holder having a plurality of slightly elliptical apertures therein, a tile burner tube comprising a cylindrical body portion having an aperture therethrough, said body including a shoulder terminating in an outwardly directed flange portion, said shoulder being slightly elliptical in shape and being adapted

to fit into a correspondingly shaped burner tube holder.

4. In combination with a gas furnace having a firing aperture therein, a burner, said burner including a burner tube holder, a plurality of tubes and a fuel manifold, said holder having a plurality of tube apertures therein, said apertures being slightly elliptical, each of said burner tubes comprising a substantially cylindrical body portion having a central aperture which is of increased diameter at one end, said body including an enlarged shoulder terminating in an enlarged flange, said shoulder being slightly elliptical, said tubes being mounted on said holder with said shoulders thereof positioned in said holder apertures and rotated to tightly engage the surfaces of said holder apertures.

5. A burner, said burner including a burner tube tile holder, said holder having a plurality of apertures therein, a plurality of tile burner tubes, each of said tubes including a cylindrical body portion having an enlarged shoulder portion thereon terminating in an enlarged flange portion, all of said portions being coaxial with each other, said body portion having an aperture therethrough, said aperture including two cylindrical portions of different diameters, the cylindrical portion of greater diameter being within the said cylindrical body portion which is of relatively small diameter, said tile burner tube being mounted on said holder with said shoulder thereof positioned in said holder apertures, said tube holder and said tubes having co-action apertures engaged to hold the tubes in place.

30 6. A burner, said burner including a plurality of tile burner tube holders, each of said tile burner tube holders including a body having upwardly directed end plates thereon, said bodies each having a plurality of rows of aligned apertures therein, said bodies having secondary apertures therein and disposed adjacent said first mentioned apertures, said secondary apertures being defined by wall portions substantially coaxial with said first mentioned apertures, said bodies at the edges being curved so that two of the bodies when adjacent form secondary apertures similar to those formed within the body, said tube holders adjacent the top and bottom thereof including lugs having apertures therein, a manifold, said manifold having legs thereon, means to secure said legs to said lugs, said manifold including a body disposed between said apertures, said manifold body having horizontal conduit portions each disposed opposite one of said apertures, a burner tile in each of said apertures and a nozzle in said conduits disposed in alignment with said burner tiles.
